(57) **CLAIM**

The ornamental design for a stiffener receiver and attachment wrap for orthotic device, as shown and described.

DESCRIPTION

FIG. 1 is a perspective view of a stiffener receiver and attachment wrap for orthotic device in accordance with the invention comprising a stiffener receiver, and a body conforming attachment wrap.

FIG. 2 is a front view of a stiffener receiver and attachment wrap for orthotic device.

FIG. 3 is a back view of a stiffener receiver and attachment wrap.

FIG. 4 is a right side view of the stiffener receiver and attachment wrap for orthotic device.

FIG. 5 is a left side view of the stiffener receiver and attachment wrap for orthotic device.

FIG. 6 is a top plan view taken looking down at the top of the stiffener receiver and attachment wrap for orthotic device; and,

FIG. 7 is bottom plan view taken looking up at the underside of the stiffener receiver and attachment wrap for orthotic device.

In the drawing figures, surface shading is used to clearly show the character and contour of surfaces of the 3-dimensional aspects of the design, and form no part of the claimed design.

The broken lines in FIG. 1 that show a humanoid figure illustrate environment. All other broken lines illustrate stitching and form no part of the claimed design.

1 Claim, 4 Drawing Sheets
